MORTIMER C. ROSENFIELD, OF CLEVELAND, OHIO.

INSULATOR-SUPPORT.

1,174,287.

Specification of Letters Patent.

Patented Mar. 7, 1916.

Application filed January 6, 1913. Serial No. 740,323.

To all whom it may concern:

Be it known that I, MORTIMER C. ROSENFIELD, a citizen of the United States, residing at Cleveland, in the county of Cuyahoga and 5 State of Ohio, have invented a certain new and useful Improvement in Insulator-Supports, of which the following is a full, clear, and exact description, reference being had to the accompanying drawings.

10 This invention relates to insulator posts, such as are employed for the purpose of supporting, through an interposed porcelain or glass insulator, a cable or heavy conductor wire. These posts are, as ordinarily constructed, fastened rigidly to a cross arm or other supporting base. In use, it frequently happens that the cable or heavy conductor or feed wire is not efficiently supported by the insulator, as by failing to rest properly 15 upon and register accurately with the groove provided therefor in the insulator proper.

It is the principal object of this invention to provide a construction of post where- 20 by the post and insulator may be very conveniently adjusted to overcome the objections noted and without the necessity for removing the post from its support.

I accomplish the foregoing results by the 25 construction illustrated in the drawings forming part hereof, wherein—

Figure 1 represents a view, partly in section and partly in elevation, of an insulator post constructed in accordance with my invention, showing the manner of its application to its support; Fig. 2 represents a sectional view corresponding to the lines 2—2 of Fig. 1; and Fig. 3 a bottom plan view of said post.

30 Describing the various parts illustrated herein by reference characters: 1 denotes the supporting base for the post, which base may be a cross-arm or any other supporting device.

45 2 denotes the insulator post generally, said post being preferably of metal and frusto-conical in shape. The post, as illustrated herein, will be provided with a cavity at its lower end and is preferably hollow 50 throughout its length. At its bottom it is provided with an inwardly projecting annular flange 3. At its top, it is provided with an externally threaded extension 4 on which there is threaded a bushing 5, preferably of 55 metal, having retaining corrugations 6 on the exterior surface thereof.

7 denotes an insulator which is cemented onto the bushing 5 and is provided with a downwardly extending skirt 8 which surrounds the upper end of the post and protects the same from the weather. 60

The insulator shown herein may be of glass, porcelain, or other suitable insulating material, and is shown as having a concaved seat 9 in its upper surface with laterally projecting wings 10 on opposite sides of said seat, said wings providing convenient means for securing a cable or conductor 11 in place on top of the insulator and in the seat thereon. The cable or conductor may 70 be secured to the wings, as by means of a wire 12.

Cooperating with the flange 3 is a clamp, said clamp consisting of a member which is adapted to be inserted into the post and to engage the flange 3 and means for securing this member to the supporting base. The member which is inserted within the base is designated by the numeral 13 and is preferably a block of metal which is generally 80 oblong in shape and of such length as to extend diametrically across the opening 14 in the bottom of the post 2 and having lateral ledges 15 adapted to engage the annular flange 3. Beneath these ledges the block is 85 rounded, as shown at 16, the surfaces 16 being cylindrical and the diameter of the cylindrical portion of the block being sufficiently less than the internal diameter of the flange 3 to provide clearance and at the same 90 time prevent the disengagement of the ledges 15 from such flange when the block is in place. The block 13 is shown as provided with a pair of threaded apertures which are adapted to receive the threaded 95 ends of a pair of bolts 17, said bolts being shown as extending through the support 1 and having heads 18 adapted to engage the bottom of such support.

By making the bolts 17 considerably 100 longer than necessary to extend through the support 1 and the block 13, one of these bolts may be shoved through the aperture provided in the support and threaded into the bottom of one of the holes in the block, 105 with the block considerably elevated above the support. The post can then be applied to the block by tilting it at such an angle as to enable the block to enter the hole 14. The post can then be straightened up and the 110 other bolt inserted through the support 1 and threaded into the bottom of the other

hole in the block 13. Both bolts may then be set up and the block be drawn down to its seat, as shown in Fig. 1. Should it be necessary or desirable to adjust the post 2 axially, it will be necessary only to unscrew the bolts 18 a short distance and, rotate the post the desired extent. Then by setting up on the bolts 18, the post may be clamped firmly in its new position.

10 By using a slotted support 1, one of the bolts may be connected to the block 13 and the block then inserted into the post and the assembly may be applied to the supporting base by inserting this bolt into one of the 15 slots. The other bolt may then be inserted into the support, threaded into the block, and both bolts set up, clamping the post in place.

By the construction described and illustrated herein, it will be apparent that I have produced an insulating post that may be adjusted to adapt it and the insulator secured thereto to varying conditions of use and, whereby the clamping parts are protected 25 from the weather, and that I have accomplished these results in and through an extremely simple and effective construction.

Having thus described my invention, what I claim is:—

30 1. The combination, with a hollow insulator post having an annular inwardly projecting flange in the interior thereof, of a support for said post, a block within said post and adapted to extend across the space 35 within and to engage opposite sides of said flange, said block being of such shape as to permit it to be inserted into the post through the space bounded by said flange, and adjustable means extending through said support and engaging said block and serving to clamp the block to the flange and thereby secure the post to the support.

2. The combination of a hollow post having an inwardly projecting annular flange 45 at its lower end, a clamping member within the post and adapted to engage said flange, said member being rotatable relative to said post, a support for said post, and means engaging the clamping member and securing 50 the post to said support and preventing the rotation of said clamping member.

3. The combination of a post having an internal annular flange near its lower end, a support for said post, and means within 55 said post and engaging the flange and adjustably securing the post to the support, said post being rotatable relative to said

means and said means being non-rotatable relative to said support.

4. The combination of a hollow post having therewithin an inwardly projecting annular flange near its bottom, a clamping member within said post and having a ledge or projection adapted to overhang the flange and engage the same, said post and clamping member being relatively rotatable, a support for the post, and securing devices extending through the opening in the bottom of the post and engaging the clamping member to secure the post to the said support, said clamping member being non-rotatable relative to said support.

5. The combination of a hollow post having therewithin an inwardly projecting annular flange, a clamping member within said post adapted to overhang the flange and engage the same, said clamping member having a plurality of threaded apertures therein, a support for the post, and a plurality of bolts extending through the bottom of the post and threaded into said apertures to secure the post to the said support.

6. The combination of a hollow post having at its bottom an inwardly projecting annular flange, a support for said post, a clamping member within the post comprising an oblong block of less width than the internal diameter of the flange and of greater length than such diameter of the flange whereby it is adapted to overhang and engage the upper surface of the flange, and a bolt extending through said support and threaded into said block.

7. The combination of a hollow post having therewithin an inwardly projecting annular flange, a support for said post, a block within said post, said block being of less width than the internal diameter of the flange and being of greater length than such internal diameter of the flange whereby ledges are provided for engaging the opposed portions of the upper surface of the flange, said block being provided below such ledges with cylindrical surfaces adapted to center the block with respect to said flange, and a bolt extending through the support and threaded into said block.

In testimony whereof, I hereunto affix my signature in the presence of two witnesses.

MORTIMER C. ROSENFIELD.
